UNITED STATES PATENT OFFICE.

CHARLES F. HUFFMAN, OF MASON CITY, IOWA.

DESIGN FOR AN AUTOMOBILE-BODY.

43,046.

Specification for Design.

Patented Sept. 24, 1912.

Application filed May 13, 1912. Serial No. 697,038. Term of patent 7 years.

To all whom it may concern:

Be it known that I, CHARLES F. HUFFMAN, a citizen of the United States, residing at Mason City, in the county of Cerro Gordo and State of Iowa, have invented a new, original, and ornamental Design for Automobile-Bodies, of which the following is a specification, reference being had to the accompanying drawings, forming part thereof.

Figure 1 is a plan view, and Fig. 2 is a

side elevation of an automobile body showing my new design.

I claim:

The ornamental design for an automobile body, as shown.

Des Moines, Iowa, April 26, 1912.

CHARLES F. HUFFMAN.

Witnesses:

H. J. BRYANT,

T. G. McDERMOTT.
